UNITED STATES PATENT OFFICE.

DONALD MILNE MANSON, OF HAMILTON, ONTARIO, CANADA.

PHONOGRAPH.

1,291,985.

Specification of Letters Patent.

Patented Jan. 21, 1919.

Application filed July 24, 1916. Serial No. 111,033.

To all whom it may concern:

Be it known that I, DONALD MILNE MANSON, of the city of Hamilton, in the county of Wentworth, in the Province of Ontario, 5 Canada, have invented certain new and useful Improvements in Phonographs, of which the following is the specification.

My invention relates to improvements in phonographs and the object of the invention is to devise electrical means whereby after a record has been played, the needle may be carried back to the beginning so that the playing of the record may be repeated, and it consists essentially of an arm secured 15 at one end to the sound box crook, magnetic means for drawing down the opposite end of the arm thereby raising the sound box and needle from the record, means counter-balancing the weight of the sound box during its return or downward movement, a 20 circuit for the magnet, a switch for making and breaking the circuit, a downwardly projecting portion carried by the taper tube, an adjustable stop designed to be turned in position to correspond with the starting 25 point of the record, and a spring connected to the taper tube and to the bracket thereof and adapted to turn the taper tube from the center of the record when the needle is 30 out of contact with the record to the starting position, whereby the taper tube is stopped from further turning by the projection thereof engaging with the adjustable stop, the parts being arranged as hereinabove more particularly explained in the following specification.

Figure 1 is a perspective view of a fragmental portion of the top of a phonograph showing a portion of my repeating means.

Fig. 2 is a section through the rear portion of a phonograph box showing my repeating means.

Fig. 3 is an enlarged detail of the junction of the sound box crook and the taper tube showing my attachment thereto.

Fig. 4 is a section through Fig. 3 along the line *x—y*.

Fig. 5 is an enlarged detail elevation of my spring attachment for turning the taper tube from the central portion of the record to the outer edge.

Fig. 6 is a longitudinal section through the counter-balancing lever.

In the drawings like letters of reference indicate corresponding parts in each figure. 55

1 indicates the usual casing of a phonograph. 2 indicates the taper tube or arm turnably mounted in the usual way in the collar 3. 4 indicates the usual bracket secured to the casing 1 and supporting the pivot 5 in the taper tube 2 in the usual way. 6 indicates the turntable of the phonograph carrying the record 7. 8 indicates the sound box crook turnably mounted in the ordinary fashion at the extending end of the taper tube 2. 9 indicates the sound box carried by the crook 8. 10 indicates the needle carried by the sound box 9. 11 indicates a pivot secured to the crook 8. 12 indicates a drum turnably mounted on the pivot 11. 13 indicates a projection carried by the crook 8. 14 indicates a projection carried by the drum 12 and adapted to engage with the projection 13. 15 indicates an arm secured at one end to the drum 12 and having at its other end an eye 16. 17 indicates a standard secured to the bottom of the casing 1 and having a forked bearing 18 at its upper extremity. 19 indicates a pivot pin carried in the bearing 18, and extending through 80 the block 20^y to form a fulcrum. 20 indicates a lever arm fulcrumed on the pivot pin 19 and comprising a central metal rod having an eye 21 at one end, an inner glass tube fitting the rod, an outer glass tube 85 spaced from the inner tube, plugs fitting the outer tube and into which the rod and inner tube extend and a charge of mercury contained between the inner and outer glass tubes. 22 indicates a hole in the frame 1. 90 23 indicates a flexible cord secured at one end in the eye 16 of the arm 15, passing through the hole 22 and secured at its other end to the lever arm 20. 24 indicates a battery. 25 indicates a magnet in proximity 95 to the end 20^x of the arm 20. 26 indicates a switch for making or breaking a circuit from the battery 24 through the magnet 25. 26^x indicates a light spring secured to the eye 21 and to the bottom of the casing 1. 100 27 indicates a coil spring under slight tension so as to have a tendency to unwind. One end of the spring 27 is secured in a hole 28 in the arm 4 and the other end is secured in a hole in the taper tube 2. 29 105 indicates a projection carried by the taper

tube 2 slightly out of contact with the frame 1. 30 indicates a stop turnably secured by the pin 31.

Having described the principal parts involved in my invention, I will briefly describe the operation of the same.

After the mechanism of the turntable revolving device has been set ready for use the turntable 6 is started in motion. The 10 taper tube 2 is then turned until the needle 10 comes into contact with the extreme outer edge of the playing portion of the record 7 at the same time turning the stop 30 on its pivot 31 so that it, the stop, is in contact 15 with the projection 29 when the needle 10 is in the starting position on the record. The stop may be turned on pivot 31 to suit any size of record.

The record is allowed to revolve until the 20 selection is finished and then if it is desired to repeat it, or if at any intermediate point it is desired to start over the switch 26 is closed, thus closing the circuit through the battery 24 and energizing the magnet 25. 25 The end 20^x of the arm 20 is thus drawn up to the magnet 25 while the opposite end is lowered to incline downward in the opposite direction allowing the mercury charge to flow to that end, drawing down on the cord 30 23, and pulling down the extending end of the arm 15. The pulling down of the extending end of the arm 15 turns the drum 12 on the pivot 11 and the projection 14 on the drum engaging with the projection 13 on the 35 crook 8 turns the crook so that the sound box 9 is raised and the needle 10 is raised from the record. The spring 27 is very light and its torque has no effect whatever while the needle 10 is on the record 7, but when 40 the needle is raised from the record by the magnetic means above described the taper tube which is delicately mounted in the collar 3 turns readily due to the unwinding tendency of the spring 27 until stopped by 45 the projection 29 on the taper tube coming in contact with the stop 30. As may readily be seen the needle is now in a position directly above the starting point of the record because the stop 30 and the projection 29 50 were set in engagement for that position and therefore by opening the switch 26 the circuit through the battery 24 is broken and the needle lowers into position for repeating the playing of the record. Such downward 55 movement of the sound box being counterbalanced by the weight of the mercury charge as the lever arm 20 is lifted to the normal inclined position. The charge then flows to the opposite end of the outer tube. 60 This arrangement allows the needle to descend with a gradual motion preventing any injury to the needle, or to the surface of the record. The spring 26^x serves to keep the projection 13 on the crook and the projec-

tion 14 on the drum 12 in engagement with 65 each other very lightly, thus compensating for the weight of the long end of the lever arm and yet permits the usual undulating movement of the needle over the surface of the record (see Figs. 1, 3 and 4.) The connection shown whereby the projections 13 and 14 engage permits the sound box 10 being turned over in a vertical direction so as to rest on the tube 2 without turning down the arm 15 below the surface of frame 1. 75

By attaching a cord to each of the contacts of the switch 26 a person may be permitted to withdraw to some distance from the phonograph to better enjoy the music, and at the completion of a selection if it is 80 desired to have it repeated it is only necessary to complete the circuit, wait a second or two to give time enough for the needle to travel from the center of the record to the edge and break the circuit, and the selection may be repeated thus as often as desired.

What I claim as my invention is:

1. In a phonograph, the combination with the sound box, sound box crook, and supporting arm, of a drum carried by the sound 90 box crook, an arm extending from the drum, a hollow lever arm containing a charge of counter-balancing fluid, a connector between the drum arm and lever arm and electrical means for raising the lever arm. 95

2. In a phonograph, the combination with the sound box, sound box crook, and supporting arm, of a drum carried by the sound box crook, an arm extending from the drum, a lever arm, and a counter balancing means 100 automatically adjustable longitudinally in relation thereto, a connector between the drum arm and lever arm and electrical means for raising the lever arm.

3. In a phonograph having a sound box, 105 means for lifting said box out of contact with a record means for returning said box to an initial position when removed from contact with the record, said lifting means comprising an arm connected to lift the box, 110 means for operating said arm to lift and lower the box at will, said means including a shiftable weight, so arranged that when the arm is operated to lift the box the weight is shifted to a position to exert its maximum 115 counter balancing of the box, and when operated to lower the box the weight is, by the lowering operation, shifted to a position where it exerts less counter-balancing effect, substantially as described. 120

4. In a phonograph having a sound box, means for lifting said box out of contact with a record, means for returning said box to an initial position when removed from contact with the record, said lifting means comprising an arm connected to lift the box, 125 means for operating said arm to lift and lower the box at will, said means including

a rolling shiftable weight so arranged that when the arm is operated to lift the box the weight is shifted to a position to exert its maximum counter balancing of the box, and 5 when operated to lower the box the weight is, by the lowering operation, shifted to a

position where it exerts less counterbalancing effect, substantially as described.
